UNITED STATES PATENT OFFICE

JAMES KIRKAL, OF LONDON, ENGLAND, ASSIGNEE TO THE BABCOCK & WILCOX COMPANY, OF BAYONNE, NEW JERSEY, A CORPORATION OF NEW JERSEY

STEAM BOILER

Application filed March 20, 1925, Serial No. 16,891, and in Great Britain July 12, 1924.

My present invention relates to steam boilers, particularly those which have provision for a reheater for steam taken from between the stages of steam turbines and the like, and is will be best understood from the following description and the annexed drawings, in which Fig. 1 is a vertical sectional elevation of one embodiment of my invention, such section being taken on the line 1—1 of Fig. 3; Fig. 2 is also a vertical sectional elevation of the same boiler as shown in Fig. 1, such section being taken on the line 2—2 of Fig. 3; Fig. 3 is a section on the lines 3—3 of Figs. 1 and 2, and Fig. 4 is a section on the line 4—4 of Fig. 2.

Like reference characters indicate like parts in the different views.

In the boiler which I have adopted for purposes of illustration, a furnace chamber 10 is provided with a chain-grate stoker 11 of the usual form. Above the chamber 10 is a bank of horizontally inclined boiler water tubes 12, which, in the form illustrated, are spaced apart to form a superheater chamber in which is located a superheater 13 of the usual type. Above the lower bank of water tubes 12 is an upper bank of water tubes 14, the bank 12 extending across the entire setting for the full width of the boiler, as shown best in Fig. 3, and the bank 14 extending only part way across the setting, also as shown best in Fig. 3.

The tubes are connected to downtake headers 15 and uptake headers 16 which, in turn, are nipped to the downtake headers 17 and the uptake headers 18 of the upper bank 14. The downtake headers 17 are nipped to the steam and water drum 19 in the usual manner and the circulating tubes 20 connect the uptake headers 18 with the drum 19. A pipe 21 leads steam from the drum 19 to the intake header 22 of the superheater 13, the steam leaving the outlet header 23 through the pipe 24 to the point of use. Above the boiler is a gas exit flue 25 extending across the boiler, such flue directing the gases horizontally into the upper end of a vertical flue 26 which leads to the lower ends of the tubes 27 of a combustion air heater located at the rear of the boiler, the combustion air to be heated

passing over these tubes from an inlet duct 28 and flowing through a duct 29 to the stoker 11, baffles 30 and 31 directing the air back and forth over the air heater tubes.

Extending from the uppermost row of the tubes 12 of the lower bank is a vertical wall 32 which is continued through the flue 25 to the right-hand end thereof where such flue joins the duct 26. Between the flue 25 and the duct 26 is a pair of vertically movable dampers 33, 34 which may be lowered by any suitable arrangement, such as the drums and chains shown.

At the left of the wall 32, as shown best in Fig. 3, is a reheater 35 comprising U-tubes connected to inlet and outlet drums, the steam to be reheated entering through the inlet pipe 36 and leaving through the outlet pipe 37.

If both of the dampers 33, 34 are lowered to their lowermost position, then the gases from the furnace rise vertically, all of such gases flowing over the lower bank 12 and the superheater 13 and then dividing, some of the gases passing over the reheater 35 and the remainder over the upper bank 14. All of the gas is led by the duct 26 to the air heater.

By positioning the dampers 33 and 34, it is obvious that the distribution of the gases as between the reheater 35 and the upper bank 14 may be regulated. Thus if the damper 34 be drawn to its closed position, all of the gases will flow across the upper bank 14 without affecting the reheater. Similarly if the damper 33 is drawn to its closed position and the damper 34 fully open, all of the gases will pass over the reheater 35 and none will pass over the upper bank 14. The dampers 33 and 34 may be set to any desired position to regulate the degree of reheating in the reheater 35 as desired, the remaining gases flowing over the upper bank 14.

Regardless of the setting of the dampers 33 and 34, all of the gases will pass over the superheater 13 and while they may be diverted in part from one side of the superheater to the other, the amount of superheat obtained from the superheater 13 will not be materially varied thereby. All of the gases will also flow over the air heater regardless

of the setting of the dampers 33 and 34, so that any waste heat will be returned to the system through the combustion air. The portion of the furnace chamber containing the 5 lower bank of tubes 12 and the superheater 13 provides a single pass for the furnace gases, which terminates in two passes disposed in parallel and which in turn communicate with the flue. One of the parallel passes 10 contains the second bank of tubes 14 while the other contains the re heater. By the expression "in parallel", it is not meant that the two passes need to be parallel to each other in the geometrical sense, but rather it is meant 15 that the two passes form different paths through which the furnace gases may pass to the flue.

The arrangement which I have shown is merely illustrative and the embodiment of 20 my invention may be widely varied.

This application is related to my copending application Serial No. 705,211, but it is to be understood that I do not intend to claim herein any of the subject matter defined in 25 the claims of said copending application, and the claims herein should be construed accordingly.

I claim:

1. A steam boiler having horizontally inclined water tubes, said tubes being divided 30 into a lower bank extending across the boiler for the full width thereof, a superheater in the lower bank, an upper bank at one side of the setting, a re heater above the lower 35 bank and alongside the upper bank, a vertical dividing wall between the upper bank and the re heater and extending to the gas outlet of the boiler, a damper at the boiler gas outlet for the passage containing the re heater, and 40 a damper at the boiler gas outlet for the passage containing the upper bank.

2. A steam boiler having horizontally inclined water tubes, said tubes being divided into a lower bank extending across the boiler 45 for the full width thereof and an upper bank at one side of the setting, a re heater above the lower bank and alongside the upper bank, a vertical dividing wall between the upper bank and the re heater and extending to the 50 gas outlet of the boiler, a damper at the boiler gas outlet for the passage containing the re heater, a damper at the boiler gas outlet for the passage containing the upper bank, and an air heater arranged to receive the 55 gases from both of said passages and ducts to lead heated air from the air heater to the boiler combustion chamber.

3. A steam boiler having horizontally inclined water tubes, uptake and downtake 60 headers for the water tubes, a steam and water drum, connections between the headers and the drum, a gas exit flue having its entrance above the connections between the uptake headers and the drum, said water tubes 65 being divided into a lower bank extending

across the boiler for the full width thereof and an upper bank at one side of the setting, a superheater in the lower bank, a re heater above the lower bank and alongside the upper bank, a vertical dividing wall between the upper bank and the re heater and extending up to and into the gas exit flue, whereby the furnace gases will flow in a continuously generally upward direction over the lower bank and then into the passages formed by the vertical wall, and a damper for each passage at the upper end of the vertical wall, whereby the quantity of gases flowing through the respective passages may be regulated.

4. A steam boiler having horizontally inclined water tubes, uptake and downtake headers for the water tubes, a steam and water drum, connections between the headers and the drum, a gas exit flue having its entrance above the connections between the uptake headers and the drum, said water tubes being divided into a lower bank extending across the boiler for the full width thereof and an upper bank at one side of the setting, a re heater above the lower bank and alongside the upper bank, a vertical dividing wall between the upper bank and the re heater and extending up to and into the gas exit flue, whereby the furnace gases will flow in a continuously generally upward direction over 90 the lower bank and then into the passages formed by the vertical wall, a damper for each passage at the upper end of the vertical wall, whereby the quantity of gases flowing through the respective passages may be regulated, an air heater to receive all the gases irrespective of the positions of the damper, and ducts to lead heated air from the air heater to the boiler combustion chamber.

5. A steam boiler having horizontally inclined water tubes, said tubes being divided into a lower bank extending across the boiler for the full width thereof and an upper bank at one side of the setting, a re heater above the lower bank and alongside the upper bank, a vertical dividing wall between the upper bank and the re heater and extending to the gas outlet of the boiler, a superheater at a lower level than the bottom of said wall, a damper at the boiler gas outlet for the passage containing the re heater, and a damper at the boiler gas outlet for the passage containing the upper bank.

6. In a steam boiler, spaced banks of boiler tubes, a primary superheater interposed between said banks, a re-heater above said banks, means for passing the gases over said primary superheater and said re-heater, means for increasing or decreasing the temperature of said re-heater without affecting the temperature of said superheater, and means for causing the gases to engage all of the superheater tubes across the boiler under every condition of operation.

7. In a steam roller, spaced banks of boiler

tubes, a primary superheater interposed between said banks, a re-heater above said banks, means for passing the gases over said primary superheater and said re-heater,
5 means for increasing or decreasing the heat applied to said re-heater without varying the heat applied to said superheater, and means for causing the gases to engage all of the superheater tubes across the boiler under
10 every condition of operation.

JAMES KEMNAL.
